UNITED STATES PATENT OFFICE.

FRANK S. BARNES, OF SUFFERN, NEW YORK.

NON-REFILLABLE-BOTTLE STOPPER.

No. 890,399.

Specification of Letters Patent.

Patented June 9, 1908.

Application filed September 20, 1907. Serial No. 393,842.

To all whom it may concern:

Be it known that I, FRANK S. BARNES, a citizen of the United States, residing at Suffern, in the county of Rockland and State of New York, have invented new and useful Improvements in Non-Refillable - Bottle Stoppers, of which the following is a specification.

This invention relates to a non-refillable bottle having a special form of neck for receiving the valve and its supporting means, and a stopper for sealing the bottle.

The invention has for one of its objects to improve and simplify the construction of devices of this character so as to be comparatively easy and inexpensive to manufacture and to permit the parts to be readily inserted, after the filling operation, for sealing the bottle and preventing refilling after the contents has been emptied.

A further object of the invention is the provision of a non-refillable bottle provided with a spherical valve and a seat or pocket therefor which is readily inserted and anchored in the bottle neck.

With these objects in view, and others, as will appear as the description proceeds, the invention comprises the various novel features of construction and arrangement of parts which will be more fully described hereinafter and set forth with particularity in the claims appended hereto.

In the accompanying drawings, which illustrates one of the embodiments of the invention, Figure 1 is a central vertical section of the neck portion of a bottle with the non-refillable device applied thereto. Fig. 2 is a plan view of the shield or valve stop. Fig. 3 is a perspective view of the valve pocket or seat and anchoring springs therefor.

Similar reference characters are employed to designate corresponding parts throughout the several views.

Referring to the drawing, 1 designates the neck of a bottle which is molded with a swell 3 at a point intermediate the ends, there being an internal annular groove 4 formed at the upper end of the swell for the purpose hereinafter to be explained. Arranged within the neck 1 is a hollow hemi-spherical pocket or seat 5 having a port 6 and snugly fitting at 7, the neck adjacent the lower end of the swell 3, thereby preventing liquid from passing out between the seat and internal surface of the neck. This pocket, which is preferably made of metal, is pro-

vided with spring arms 8 extending upwardly therefrom and arranged ninety degrees apart and having their upper ends formed into outwardly extending lugs 9 that are adapted to engage in the annular groove 4. Arranged above the valve to form a stop therefor is a disk or shield 9' having suitable perforations 10 through which the liquid can be poured out, there being provided on the under side of the disk, pockets 11 through which the lugs 4 project. The pockets 11 are open at the bottom side of the disk 9' and also at the periphery, the bottom openings being of such size to permit the lugs 4 to be inserted into the pockets and then permitted to spring outwardly and project beyond the periphery of the disk, as shown.

In practice, the bottle is filled in any approved manner and the bottler then takes the device shown in Fig. 3 and drops a spherical valve or ball 18 into the pocket 5, and next compresses the springs 8 inwardly so that the upper ends thereof can be engaged in the pockets 11 of the disk 9'. The unitary structure thus formed, is thrust into the upper end of the bottle neck and pushed downwardly to its normal position by any suitable means. During the insertion of the device, the lugs 9 engage the internal surface 85 of the neck and are forced inwardly until the annular groove 4 is reached, whereupon the springs 8 move outwardly and cause the lugs 9 to engage in the said groove. After the device is thus inserted, a suitable sealing stopper is placed in the upper end of the neck so that the contents can not leak out if the bottle is upset.

From the foregoing description, taken in connection with the accompanying drawing, the advantages of the construction and of the method of operation will be readily apparent to those skilled in the art to which the invention appertains, and while I have described the principle of operation of the invention, together with the apparatus which I now consider to be the best embodiment thereof, I desire to have it understood that the apparatus shown is merely illustrative and that such changes may be made when desired, as are within the scope of the claims.

Having thus described the invention, what I claim is:—

1. A non-refillable bottle comprising a neck having an internal annular groove, a valve seat fitted in the neck, means attached to the seat and engaging in the groove for

holding the seat in position, a ball valve co-operating with the seat, and a member for holding the valve in the neck, said member being separate from the valve seat and connected therewith by the said means and held in position by the latter.

2. A non-refillable bottle comprising a neck having an annular groove, a valve seat, a valve co-operating with the seat, a member for limiting the movement of the valve, and a common means for holding the member and seat in position.

3. A non-refillable bottle, comprising a bottle neck, a valve seat therein, a valve co-operating with the seat, a perforated member for permitting the liquid to pass out of the neck and serving as a stop for the valve, springs attached to the seat and arranged to anchor the seat and member in the neck.

4. A non-refillable bottle comprising a neck, a stopper therefor, a valve seat, a valve, an apertured disk above the seat and serving as a stop for the valve, resilient members attached to the seat and removably connected with the disk, and means engaged by the members for holding the disk and seat in position.

5. A non-refillable bottle comprising a neck having an annular groove and a swell below the groove, a valve seat fitting the

neck at the bottom end of the swell, a ball valve for the seat, an apertured disk provided with pockets opening at the periphery and bottom of the disk, resilient members attached to the seat and having laterally bent ends extending through the pockets of the disk and engaging the annular groove of the neck, and a stopper for the neck.

6. In a non-refillable bottle, the combination of a bottle neck having an internal 40 groove, a valve therein, a concaved valve seat consisting of a cup-shaped member having an opening, and parallel springs secured to the seat and arranged to prevent lateral movement of the valve, the extremities of 45 the springs being bent laterally to engage in the said groove.

7. In a non-refillable bottle, the combination of a bottle neck, a valve, a concaved valve seat consisting of a cup-shaped member having an opening, springs connected with the seat and arranged to hold the latter in position, and means held in the neck by the springs for preventing access to the valve.

In testimony whereof, I affix my signature 55
in presence of two witnesses.

FRANK S. BARNES.
